SANDBOX CLOSURE MEANS

Martin P. Blomberg, Hinsdale, Ill., assignor to
 General Motors Corporation, Detroit, Mich., a
 corporation of Delaware

Application April 19, 1943, Serial No. 483,610

7 Claims. (Cl. 291—38)

This invention relates to closures for sand boxes such as are used on railway locomotives, and one of the objects of the invention is to provide such a closure wherein the entrance of moisture into the interior of the sand box will be positively prevented, to insure that the sand therein may be kept in a dry condition in order that it will always flow freely through the pipes which conduct it down to the track adjacent the locomotive wheels.

In the embodiments of my invention disclosed herein, the sand box is located inside the locomotive body but is separate therefrom, being spaced a slight distance away from the side wall of the body. The sand box has a filling opening formed near its upper end and a door is provided to close this opening, while another door serves to close a registering opening in the side wall of the body, the latter opening being provided to permit filling the sand box from the exterior of the locomotive. Sealing strips of resilient material are provided between the inner door and the sand box and between the outer door and the body wall to prevent the passage of any moisture therebetween when the doors are in closed position.

A tubular sleeve of resilient material secured around the edge of the filling opening in the body side wall extends inwardly to the wall of the sand box where it is secured around the edge of the filling opening therein. This forms a tubular passageway through which the sand passes on its way into the sand box, the sleeve serving to prevent air from outside of the vehicle or dust from the sand from entering into the locomotive body when the sand box is being filled.

In one form of my invention, when the outer door is in closed position, a part secured to its inner surface engages a member carried by the inner door, which member through the action of a spring serves to exert constant pressure on the inner door to hold it tightly against the resilient sealing strip.

Other objects and advantages of the invention will be apparent upon reference to the specification and accompanying drawings, in which:

Fig. 1 is a side elevation of the front portion of a locomotive body of the Diesel-electric type, showing my improved sand box closure means associated therewith.

Fig. 2 is a fragmentary side elevational view, on a larger scale, of the sand box closure means.

Fig. 3 is a sectional view, taken on the line 3—3 of Fig. 2.

Fig. 4 is a sectional view, taken on the line 4—4 of Fig. 2.

Fig. 5 is a view corresponding to Fig. 2 but

showing a somewhat different form of my invention.

Fig. 6 is a sectional view taken on the line 6—6 of Fig. 5.

5 Fig. 7 is a sectional view taken on the line 7—7 of Fig. 5.

Fig. 8 is a sectional view taken on the line 8—8 of Fig. 7.

The reference numeral 10 indicates the side 10 wall of the locomotive body, and 12 is a sand box which is located within the body. As best shown in Fig. 4, the wall 14 of the sand box is spaced a slight distance away from the side wall 10 of the body, and a plate 16 having a relatively large 15 opening 18 formed therein is welded to the wall 14. The opposite wall 20 of the sand box extends diagonally as at 22 at its upper end and then horizontally as at 24 to form a top for the sand box, this top being welded to the plate 16. 20 The wall 20 also is bent around to form side walls 26 which are welded to the wall 14. The lower portion of the sand box is not shown since it forms no part of the present invention.

Secured inside the opening 18 in the plate 16 is 25 a channel member 28 which is bent so that it extends across the top and down each side of the opening, the outer leg 30 of the channel being welded to the plate 16. A sealing strip 32 formed of any suitable resilient material is secured in the 30 bottom of the channel by fasteners 34, this strip when in uncompressed condition extending beyond the inner leg 36 of the channel. 38 is a door which is pivotally connected to the plate 16 by a hinge 40, the lower edge of the door being bent over to form a flange 42 to which the hinge is secured. Welded to the outer face of the door are vertically extending stiffening members 44 which are of channel shape in cross section, and a handle 46 has its ends welded to the members 44. Secured to the inner face of the door by welding is 35 a U-shaped chute 48 which serves to support a screen 50 which is secured to its lower edge, there being a small plate 52 welded to the lower portion of the door and to the sides of the chute 48 to keep 40 the sand from getting into the hinge 40 and to support the edge of the screen adjacent the door. The purpose of the screen is of course to keep 45 lumps of sand or foreign matter from entering the sand box, the sand being poured into the chute 48 when the door is in the open position shown in dash-and-dot lines in Fig. 4 and flowing down through the screen into the sand box.

As best shown in Fig. 4, the door 38 is held in closed position by the following mechanism. Secured to the outer face of the plate 16 above the

door is a bracket 54 having spaced side portions 56. Between these side portions a C-shaped member 58 is pivotally mounted, there being a pivot connection 60 between the member 58 and each side portion, the pivot however not running from one side to the other of the bracket, for a reason to be presently explained. A roller 62 is pivotally supported at one end of the member 58, while another roller 64 is pivotally supported at the other end thereof. A tension spring 66 has one end secured to a hook 68 provided on the bracket 54, the other end of the spring being connected to a lug 70 bent inwardly from the member. The arrangement of the points of connection of the spring to the bracket and to the member 58 is such that when the member is in the closed position shown in full lines in Fig. 4, the spring will extend on one side of the pivot point 60 and will tend to draw the roller 62 firmly against the door, while when the door is pulled toward open position and the member 58 assumes the position shown in dot-and-dash lines in Fig. 4, the spring will be swung past the pivot point so that it will extend on the other side thereof and will then serve to hold the member in that position thereby allowing the door to be freely opened. In other words, the spring 66 functions as an over-center spring to hold the member 58 in either open or closed position, and in the latter position serves to continuously draw the door firmly against the sealing strip 32 compressing the latter slightly as shown in Fig. 4, thereby preventing the entrance of moisture into the sand box. It will be seen that when the member 58 is in the open position shown in dot-and-dash lines in Fig. 4, the roller 64 has been swung around to a position wherein it will lie in the path of the door when the latter is moved to closed position, and will consequently be engaged by the inner face of the door during such closing movement with the result that the member 58 will be swung around its pivot point 60 until the spring passes beyond such pivot point, whereupon the spring will serve to pull the member in the direction which will cause the roller 62 to bear against the door, thereby assisting in moving the latter to closed position and firmly holding it in that position.

To permit the filling of the sand box from the outside of the locomotive, an opening 72 is formed in the body side wall 10. A frame is provided for this opening, which frame consists of angle members 74 and a plate 76 having an opening 78 formed therein, the angle members and the plate being drawn toward each other by bolts 80 so that they are clamped against the side wall 10, there being a gasket 82 of resilient material interposed between the long legs 84 of the angle members and the side wall and a similar gasket 86 between the side wall and the plate 76, the latter abutting against the ends of the short legs 88 of the angle members.

Secured to the ends of the bottom angle members are lugs 90 through which extends a long pin 92 which is held in place by nuts 94 threaded thereon. 96 is a door which has a piece of tubing 98 welded to its lower edge, the tubing fitting over the pin so that the door will be pivotally supported thereon. A strip 100 of resilient material is secured to the inner face of the door adjacent the opening in the frame so that when the door is in closed position, a weathertight joint will be provided between the door and the frame.

This door is held in closed position by members 58 and associated parts which are identical with those described in connection with the in-

ner door 38, the only differences being that two of holding members are employed instead of one and they being located on the inside of the door instead of on the outside. The brackets 54 in this case are secured to U-shaped supports 102 and 104, the ends of which are welded to the inner face of the door. These holding members operate in the same general manner as that previously described, the rollers 62 in this case however bearing against the inner face of the plate 76 when the door is in closed position and thereby serving to draw it tightly against the sealing strip 100. When the door is moved to open position, the members 58 will be swung around the pivot points 60 until the springs pass over such points, whereupon the members will be pulled by the springs to a position wherein the rollers will, during the latter part of the closing movement of the door, engage the long legs 84 of the angle members, and a continuation of the closing movement will cause the springs to pass over center again and then serve to draw the rollers 62 against the plate 76 to firmly hold the door in closed position against the sealing strip 100.

The upper and side edges of the door are bent over to form flanges 106, and a hand hole 108 is formed in the central portion of the door. A cup-shaped member 110 is welded to the inner face of the door to provide a space for the fingers of the operator's hand when the door is to be opened or closed, the member 110 extending beyond the edge 112 of the hand hole in order that the portion of the door adjacent the edge 112 may be grasped by the operator during the opening or closing movements of the door. The purpose of locating the holding members for the door 96 on the inside thereof, and of providing the hand hole in the door rather than placing a handle theron, is to avoid having any parts projecting outwardly from the door, it being desirable that the outer surface of the locomotive body wall be maintained as smooth as possible. The tubing 98 is of oval shape in cross-section in order that there may be clearance at each side 45 of the pin 92, which clearance is provided to permit the door to be drawn tightly against the sealing strip 100 by the holding members.

Welded to the plate 76 adjacent the outer edge thereof is an oval-shaped flange 114 to which is secured a ring 116 which is of round cross-sectional shape. A similar flange 118 is welded to the plate 76 opposite the band 114 and it has secured to it a ring 120 which is like the ring 116. Extending over the space between the flanges 114 and 118 is a sleeve 122 of any suitable resilient material, and this is held in place by having springs or wires 124 sewed or otherwise secured in its edges, these springs or wires extending behind the rings 116 and 120 and serving to draw the sleeve over said rings. The purpose of the sleeve is to provide a yieldable closure between the edges of the opening in the body side wall and the opening in the sand box, to prevent air from outside the vehicle or dust from the sand from entering the space inside of the body when the sand box is being filled, which of course requires that the door 96 be opened. The reason it is desirable to have the sleeve 122 formed of resilient material is that the sand box, being formed as a receptacle which is separate from the body framing rather than a part thereof, will tend to move slightly relative to the body side wall during operation of the locomotive, and the resilient sleeve will accommodate such movement.

In Figs. 5 to 8 there is shown another form of my invention, which may be considered as being the preferred form. In describing this form of the invention, the same reference numerals are used to refer to parts which are the same as those used in the form first described. Therefore, the numeral 10 designates the side wall of the locomotive body and 12 is a sand box located within the body, the side wall 14 of the box being spaced from the wall 10 as in the other form. 16 is a plate welded to the side wall and having a relatively large opening 18 formed in it. The opposite wall 20 of the sand box extends diagonally as at 22 at its upper end and then horizontally as at 24 to form a top for the box, this top being welded to the plate 16. The wall 20 also is bent around to form side walls 26 which are welded to the wall 14.

The plate 16 has a channel-shaped portion 126 formed in it across the top and down each side of the opening 18. The sealing strip 32 which is formed of any suitable resilient material, is secured in this channel by fasteners 34, this strip when in uncompressed condition extending beyond the end of the inner leg 128 of the channel. 130 is a door which is pivotally connected to the plate 16 by hinge 40, the lower edge of the door being bent over to form a flange 42 to which the hinge is secured. Connected to the inner face of the door by welding is a U-shaped chute 48 which serves to support a screen 50 which is secured to its lower edge. 52 is a plate welded to the inner surface of the lower portion of the door and to the sides of the chute 48 to keep the sand from getting into the hinge 40 and to support the edge of the screen adjacent the door. Welded to the outer face of the door is a channel-shaped member 132 which serves to stiffen the door and also serves an additional purpose, to be described presently.

Opposite the door 130, the side wall 10 has a large rectangular shaped opening 72 formed in it. A frame fits within this opening, which frame consists of a channel-shaped member 134 having a flange 136 extending outwardly therefrom, and a plate 138 secured together by bolts 140, the latter serving to clamp the side wall between the flange and the plate, there being strips 82 of resilient material interposed between these parts. The plate 138 has a rectangular shaped opening 142 formed in it. Secured to the inner leg of the channel 134 by rivets 144 is a gasket 146 of resilient material.

Welded to each side of the lower portion of the flange 136 of the frame are lugs 90 through which a long pin 92 extends, which pin is held in place by nuts 94 threaded on the ends thereof. 148 is a door having a piece of tubing 98 of oval cross-sectional shape welded to its lower portion, the tubing fitting over the pin so that the door will be pivotally supported thereon. The outer edge of the door is bent inwardly as at 150 so that it extends into the space between the legs of the channel 134 to protect the gasket 146 and to improve the appearance of the door.

The central portion of the door 148 is pressed inwardly to form a recess 152 within which is located a handle 154 for operating and locking the door. As best shown in Fig. 7, this handle has a shank 156 which is journaled in a hub 158 of a housing 160 which is secured by bolts 161 to brackets 162 welded to the inner surface of the door, the hub extending through a hole formed therein. The shank has a square hole formed in it, and a squared portion 163 of a shaft 164

extends through this hole, the handle 154 being held in place thereon by nut 166. The other end of the shaft extends into the housing 160 and has a rollback member 168 welded or otherwise secured to it. Between the rollback and the end of the shank 156 are located a spacer sleeve 170 and a washer 172, and at the end of the shaft a collar 174 is secured thereto, this collar being journaled in a bore 176 formed in a cover 178 which is secured to the housing by screws 180.

As best shown in Figs. 5 and 6, the housing 160 extends substantially all the way across the door 148 and has at latch bolt 182 slidably mounted in its left hand end below the center of the shaft 164, while a latch bolt 184 is slidably mounted in the right hand end of the housing above the center of the shaft. The latch bolt 182 has a bar 186 secured to it and at the inner end of this bar a projection 188 is formed which is adapted to be engaged by the arm 190 on the rollback 168 to retract the latch bolt when the handle is turned. A compression spring 192 bearing against the projection 188 normally keeps the latch bolt in extended position. The latch bolt 184 has a bar 194 secured to it, which bar has projection 196 extending behind arm 198 on rollback 168, a compression spring 200 bearing against projection 196 to normally hold the latch bolt 184 in extended position. The bar 194 rests on top of the spacer sleeve 170 and rolls thereon when the latch bolt is retracted.

As shown in Fig. 6, when the door 148 is in closed position, the latch bolts 182 and 184 bear against members 202 which are secured to striker plates 204 connected to the channel 134 by screws 206. The members 202 have angularly extending surfaces 208 formed thereon which cooperate with correspondingly shaped angular surfaces 210 formed on the latch bolts to draw the door tightly against the resilient gasket 146 thereby effecting a weather-tight seal all around the edge of the door opening.

When the door 148 is in closed position, a wear plate 212, secured to the cover 178 by screws 214, 45 bears against a lever 216 which is pivotally connected by bolt 218 to a bracket 220 welded to the outer face of door 148. A compression spring 222, pivoted at one end on a pin 224 secured to the door and at the other on a pin 226 carried by the lever 216 tends to swing the latter to the left about the pivot point 218 as viewed in Fig. 7, but when the outer door 148 is in closed position, the action of the wear plate 212 bearing against the lever compresses the spring causing the latter 50 to press the door 130 tightly against the resilient sealing strip 32 to produce a tight seal around the edge of the door 130, in order to prevent the entrance of moisture into the interior of the sand box.

To open the outer door 148, the handle 154 is turned in a counterclockwise direction which causes the rollback arms 190 and 198 to pull the bars 186 and 194 respectively toward the center of the door, thereby retracting the latch bolts 182 and 184 so that the door may be swung outwardly and downwardly about its pivot point 92. This of course releases the pressure against the lever 216 which then swings to the left as viewed in Fig. 7 until it engages a stop 228 which is welded to a flange 230 bent outwardly at the upper edge of the door. The operator may then take hold of the pressure lever which also serves as a handle and by pulling on it may move the inner door 130 to open position, which is shown in the dot-and-dash lines in Fig. 7. It will be seen that when in

this position, the channel stiffening member 132 serves also as a bumper, bearing against the lower part of the outer door frame 134 to limit outward movement of the door 130 so that the chute 48 will be in correct position to receive sand being poured into the chute, the sand passing through the screen 50 as it falls downwardly into the sand box.

When the doors are to be closed, the inner door is first swung up into closed position. It will be noted that the plate 16, which contains the filling opening for the sand box and to which the door 130 is hingedly connected, is in a slightly inclined position so that the upper part of the door 130 must be swung a little over the center of the hinge 40, which results in this door staying in closed position until the outer door is closed and the wear plate 178 again bears against the pressure lever 216 to positively hold the inner door in closed position.

When the outer door is being swung to closed position, it will be noted that since the latch bolt 182 is closer to the hinge connection 92—98 than is the latch bolt 184, it will first engage its striker plate 204 and will be forced inwardly against the action of spring 192 before the latch bolt 184 engages its striker plate. This makes it somewhat easier to close the door than would be the case if the springs behind both latch bolts had to be compressed at once.

Secured to the plate 138 adjacent the outer edge thereof is a ring 232 having an outwardly extending flange 234 formed thereon, while a similarly shaped ring 236 provided with a flange 238 is secured near the outer edge of plate 16. As in the first described form of the invention, 122 is a sleeve of any suitable resilient material which is held in place by having springs or wires 124 sewed or otherwise secured in its edges, which springs or wires extend behind the flanges 234 and 238, the purpose of the sleeve being the same as in the other form.

While specific embodiments of the invention have been shown and described, it will be understood that various changes in the arrangement and details of the structure may be made without departing from the spirit and scope of the appended claims.

I claim:

1. In combination with a vehicle body having a side wall, said wall having an opening formed therein, a sand box located inside said body and spaced from said wall, said box having a filling opening registering with the opening in the wall, doors for each of said openings, and a flexible member extending from the inner face of the wall to said sand box, said member surrounding said openings to provide a tubular passageway through which sand may be supplied to said box from the exterior of the body.

2. In combination with a vehicle body having a side wall, said wall having an opening formed therein, a sand box located inside said body and spaced from said wall, said box having a filling opening registering with the opening in the wall, doors for each of said openings, and a closure member of flexible material extending across the space between the inner surface of the wall and the sand box around the edges of said openings, said member forming a tubular passageway through which sand may be supplied to said box from the exterior of the body.

3. In combination with a vehicle body having

a side wall, said wall having an opening formed therein, a sand box located inside said body and spaced from said wall, said box having a filling opening located opposite the opening in the wall, doors for each of said openings, and a closure member of flexible material extending across the space between the inner surface of the wall and the sand box around the edges of said openings, said closure member preventing the entry of outside air into the interior of the vehicle body when the doors are opened to permit filling of the sand box.

4. In combination with a vehicle body having a side wall, said wall having an opening formed therein, a sand box located inside the body and spaced from said wall, said box having a filling opening registering with the opening in the wall, doors for each of said openings, an annular flange extending inwardly from the wall around the opening therein, a second annular flange extending from the sand box toward the first named flange, and a sleeve of flexible material having its ends secured to said flanges, said sleeve forming a tubular passageway through which sand may be supplied to the box from the exterior of the body.

5. In combination with a vehicle body having a side wall with an opening formed therein, an outer door adapted to close said opening, a sand box located inside said body and spaced from said wall, said box having a filling opening registering with the opening in said wall, an inner door adapted to close the opening in said box, and resilient means carried by the inner door adapted to be engaged by a portion of the outer door when the latter is in closed position, whereby the inner door will be tightly held in closed position.

6. In combination with a vehicle body having a side wall with an opening formed therein, an outer door adapted to close said opening, a sand box located inside said body and spaced from said wall, said box having a filling opening registering with the opening in said wall, an inner door adapted to close the opening in said box, a lever pivotally supported on the outer face of said inner door, and resilient means located between the lever and the inner door, said outer door when in closed position being adapted to engage the free end of said lever whereby said resilient means will be compressed and will exert pressure against said inner door to tightly close the opening in said sand box.

7. In combination with a vehicle body having a side wall with an opening formed therein, an outer door adapted to close said opening, a sand box located inside said body and spaced from said wall, said box having a filling opening registering with the opening in said wall, a resilient sealing strip extending around the edge of the latter opening, an inner door adapted to seat against said sealing strip, a bracket secured to the outer face of the inner door, a lever pivotally supported on said bracket, and a spring located between said lever and said inner door, said outer door when in closed position being adapted to engage the free end of said lever whereby the latter will be swung toward the inner door compressing said spring and causing the latter to exert pressure against said inner door to hold the latter against said sealing strip thereby tightly closing the opening in said sand box.

MARTIN P. BLOMBERG.
